CLAIM

The ornamental design for a container with swirled side walls, as shown and described.

DESCRIPTION

FIG. 1 is a top isometric view of a container with swirled side walls, showing my design.

FIG. 2 is a top view thereof.

FIG. 3 is a front elevation view thereof.

FIG. 4 is a right side elevation view thereof, the left side elevation being a mirror image thereto.

FIG. 5 is a rear elevation view thereof; and,

FIG. 6 is a bottom isometric view thereof.

The broken lines illustrate environmental elements of the container with swirled side walls which form no part of the claimed design.
